UNITED STATES PATENT OFFICE.

STEPHEN J. HEINRICH, OF BELLEVUE, PENNSYLVANIA, ASSIGNOR TO
AMERICAN ELECTRIC ALARM COMPANY, OF PITTSBURG, PENNSYLVANIA, A CORPORATION OF NEW JERSEY.

FIRE-ALARM BOX.

No. 816,465.

Specification of Letters Patent.

Patented March 27, 1906.

Application filed April 26, 1904. Serial No. 204,960.

To all whom it may concern:

Be it known that I, STEPHEN J. HEINRICH, a subject of the Emperor of Austria-Hungary, residing at Bellevue, in the county of Allegheny and State of Pennsylvania, have invented certain new and useful Improvements in Fire-Alarm Boxes, of which the following is a specification, reference being had therein to the accompanying drawings.

10 This invention has relation to fire-alarm boxes, and has for its object the provision of novel means for successively breaking the circuit of a fire-alarm system at regular intervals after the boxes have been pulled, so as to 15 indicate to the operator at the central station the number of the particular box from which the alarm has been sent.

A further object of my invention is to provide means in a fire-alarm box for preventing 20 simultaneous operation of a plurality of fire-alarm boxes arranged on the same circuit.

In a system fitted with fire-alarm boxes constructed according to my improvement each box when pulled to send in an alarm so 25 effects the electric circuit that during the time this box is in operation no other box on the same circuit can be thrown into operation, and my improvement therefore constitutes a non-interfering fire-alarm box, it being understood that all the boxes in a system 30 employing my improvements are of the same construction, so that each box will control the circuit and prevent any of the other boxes therein from being sounded while it is 35 in operation.

My invention consists in the novel construction, combination, and arrangement of parts hereinafter described and claimed.

Referring to the accompanying drawings, 40 Figure 1 is a perspective view of a fire-alarm box constructed according to my improvement, the outer door thereof being open. Fig. 2 is a front elevation of a receptacle which is arranged in the box shown in Fig. 1 and which contains the operating mechanism of my improved box. Fig. 3 is a vertical sectional view of the receptacle shown in Fig. 2. Fig. 4 is a vertical transverse sectional view of a part of the operating mechanism on the line $x-x$ of Fig. 3 looking toward the back of the receptacle. Fig. 5 is a similar view on the same line looking toward the front of the receptacle. Fig. 6 is a detail perspective view of a part of the mechanism shown in Fig. 5. Figs. 7 and 8 are diagrammatical views showing the electric circuits of my improved box. Fig. 9 is a rear view of the inner door of the box shown in Fig. 1. Fig. 10 is a vertical sectional view of the door shown in Fig. 9. Fig. 11 is a plan view, and Fig. 12 a transverse sectional view, of the main gear-wheel and locking-cam of the operating mechanism shown in Figs. 2 to 5.

65 The outer casing of the box (designated 1) is of the usual configuration and is provided with a hinged outer door 2, carrying the usual glass-faced compartment 3 for the reception of a key which opens the lock 4 of the door. The door 2 carries an inwardly-projecting pin 5, which when the door is closed contacts with a movable pin 6, that passes through the inner door 7 and, as will be hereinafter described, operates a switch which 70 throws the electrical appurtenances of the box into or out of circuit with the main line accordingly as the door 2 is opened or closed.

75 The inner door 7 is formed with a curved slot 8, through which projects a hook 10, carried by an arm 9, by means of which the mechanism within the box is operated when an alarm is to be sounded. The arm 9 is pivoted at 11 on the inside of the door 7, and a spring 12 is secured to the arm 9 and to a pin 13 on the door, the said spring serving to restore 80 the arm 9 to its normal position after the box has been pulled. A dog 14 is pivoted on the arm 9 and pressed by a spring 15, the said dog 85 engaging the curved winding-arm 16 of the operating mechanism. The winding-arm 16 is shown in dotted lines in Fig. 9, and it will be observed that the arm 9 and the winding-arm 16 are pivoted at substantially opposite points and that the dog 14 is located intermediate of these two pivotal points, so that 90 as the arm 9 is pulled downwardly the dog 95 will gradually move toward the end of the winding-arm and will eventually slip off of the same, thus releasing the winding-arm at the termination of the downward movement 100 of the arm 9 and preventing the winding-arm from being held in its depressed position. The winding-arm 16 is carried on the end of a shaft 17, which, together with the other moving parts of the winding mechanism, is journaled in the front plate 18 and the rear plate 105

19 of the supporting-frame of the operating mechanism. Upon the shaft 17 and between the plates 18 and 19 is mounted the winding-segment 20, that meshes with a pinion 21, 5 carried by a shaft 22, to which shaft is secured one end of a volute spring 23, the other end thereof being attached to a pin 24 on the plate 19. The winding-segment 20 is formed with a hooked arm 25, the end of which when 10 the winding-segment is at rest engages with a post 26, extending between the plates 18 and 19. A gear-wheel 27 is loosely mounted on the shaft 22, and the said gear-wheel communicates motion through a pinion 28, a gear-wheel 29, and a pinion 30 to an escape-wheel 31, the movement of which is governed by a pawl 32, mounted on a shaft 33, which carries an arm that is provided with adjustable weights 35 35, by means of which the rate of 15 movement of the pawl can be regulated. A cam-disk 36 is fast on the shaft 22 and revolved thereby, and said cam-disk is formed with a ratchet-tooth 37, which when the shaft 22 is turned by pulling the winding-arm 16 20 engages a pin 38 on a dog 39, that is loosely mounted and has a limited movement on a shaft 40 and is drawn downwardly by a spiral spring 41. The shaft 40 has fixed upon it a rocking lever 42, which carries the armature 43 of an electromagnet 44, and said lever 42 has a shoulder 42', that is engaged by a similar shoulder 39' on dog 39, so that when the 25 dog is forced downwardly by the turning of cam-disk 36 the armature will be elevated and caused to contact with the cores of electromagnet 44. The shaft 40 also carries a second rocking arm 45, which is cut away on one side, as indicated at 46, leaving a tooth 47 with a beveled end, this rocking arm being 30 shown in the detail perspective view, Fig. 6.

An insulating-plate 48 is mounted on the plate 18, and upon said insulating-plate are mounted two pivoted contact-arms 49 50, these contact-arms being provided with platinum contact-points 51 and being drawn toward one another by spiral springs 52 53. The 35 contact-arm 50 has a tooth 54 on its outer side, which is successively engaged by the pins 55 on the face of an insulated signal-wheel 56, that is carried on a shaft 57, said shaft also carrying the pinion 28 and the gear-wheel 29. Each of the pins 55 is semicircular in form, the flat side of the pin being uppermost on that side of the wheel where the pins engage with the tooth 54, and the formation of these pins im- 40 parts a comparatively slow movement in one direction to the arm 50, while allowing the same to return to its normal position rapidly. When the arm 50 is moved by the contact of one of the pins 55 with the tooth 54, the contact-point of this arm slides along the contact-point of the contact-arm 49, and this sliding movement keeps the contact-points clean and avoids the accumulation of dust or the formation of oxids thereon. The movement 45

of the contact-arms 49 and 50 toward the wheel is limited by pins 57' 58', which are so located that when the arm 50 has been released from engagement with one of the pins 55 and the arms 49 50 have been returned to 70 their normal position in contact with the pins 57' 58' the contact-points on the arms will be separated.

The winding-segment 25 carries a lug 25', which when the box is at rest lies in the cut-away portion 46 of the rocking arm 45 back of the tooth 47, and thus the box is prevented from being wound except when the armature 43 is in contact with the cores of the electromagnet 44, in which position the shaft 40 being turned by the upward movement of the armature 43 the lug 25' is out of the path of the tooth 47, and the winding-segment may be turned by pulling the hook 10.

The mechanism above described is contained within a circular casing 59, that is fastened in the receptacle that contains all of the signaling mechanism, said receptacle being designated 60, and the casing, if desired, being provided with a glass front to protect 90 the operating mechanism from dust. In the lower left-hand corner of the receptacle 60 is arranged the switching mechanism, the said mechanism comprising four contact-points, lettered, respectively, 61, 62, 63, and 64, 95 these contact-points being mounted on an insulated base 65. A swinging contact-arm 66 is also mounted on the base 65, and said arm carries two contact-plates, lettered, respectively, 67 and 68, and the swinging arm is 100 drawn outwardly by a spiral spring 71 and is connected to the pin 6, which projects through the inner door 7 of the box and is engaged by the pin 5 on the outer door when the said outer door is closed. The plates 67 105 68 are of such width that each of them will bridge two of the contact-points 61 62 63 64, and in the normal position of parts the plate 67 bridges the two contact-points 62 63, the contact-plate 68 being then in engagement 110 only with the contact-point 64, and when the outer door 2 of the box is opened the switch-lever 66 swings outwardly, and the plate 67 bridges the contacts 61 62, while the plate 68 bridges the contacts 63 64. A lightning-arrester 72 and an electric call-bell 73 are arranged in the receptacle 60; but as these parts are of the usual and well-known construction they need not be specifically described. Binding-posts 74 75 76 77 are arranged on 115 the casing 59, and these binding-posts serve for the attachment of the wires within the box, while binding-posts 78 79 on the call-bell and binding-posts 80 81 82 on the lightning-arrester 72 serve a like-purpose.

A spring-tongue 83 is mounted on an insulated post 84 on the plate 18, and said tongue is caused when the box has been pulled to contact with a similar tongue 85, which is mounted on an insulated post 86 the move- 120

- ment of the tongue 83 being effected by an arm 87, carried on the shaft 22, this arm being so located that it will operate upon spring-tongue 83 and force it into contact with the 5 spring-tongue 85 when the box has run down at the completion of the operation of sounding an alarm, the purpose of these spring-tongues being to short-circuit the contact-levers 49 50 when the same are not in action, so 10 as to preserve a constant circuit through the main line and obviate the danger of abnormally-heavy currents passing through the levers 49 50 when the box is in passive condition. The circuits of the box when the parts 15 are in their active and passive positions are shown in Figs. 7 and 8, and referring to these figures the sign plus (+) indicates the incoming line and the sign minus (—) indicates the outgoing line of the main circuit. Beginning 20 at the plus sign of the incoming line of Fig. 7, which shows the mechanism of the box in its passive position, the circuit proceeds by a wire 87 to the binding-post 82 of the lightning-arrester, where it finds an open circuit, and 25 from wire 87 a wire 88 leads to the contact-point 62 of the switch. Thence the circuit proceeds across the plate 67 to the contact 63 and thence by a wire 89 to the binding-post 86, thence by a wire 90 to the insulated post 30 86, and the contact-tongues 83 85 being in contact the circuit proceeds by way of tongue 83 to the insulated post 84, from whence a wire 91 leads to the binding-post 77, from which a wire 92 leads to the binding-post 80 35 of the lightning-arrester, from whence a wire 93 leads to the outgoing wire 94.
- From the foregoing it will be observed that a complete circuit is maintained in the box while the mechanism therein is inactive and 40 that the operative parts of the signaling mechanism are short-circuited through tongues 83 85. Referring now to Fig. 8, where the parts are shown in their active position, and beginning, as before, with the plus sign of the incoming circuit 87, the circuit is, as before, conducted to the contact-post 62 by the wire 88, and from thence circuit is established by the plate 67, which now bridges the contact-posts 61 and 62, to the contact- 45 post 61, from whence a wire 95 leads to the binding-post 75, and from thence a wire 96 leads to the electromagnet 44, from which a wire 97 leads to the binding-post 74, and from thence a wire 98 leads to the binding-post 79 50 of the call-bell, whence the current, after passing through the electromagnet of the call-bell, goes to the binding-post 78, by a wire 99 to the contact-post 64, and through the plate 68, which now connects the post 64 with the post 63, to the said post 63, from which a wire 89 leads to the binding-post 76, through which the current passes to the wire 90, to insulated post 86, and the tongues 83 85 being now out of contact the current passes by a wire 100 to 55 the contact-arm 50, thence the contact-point of arm 50, being in contact with the contact-point of the arm 49, the circuit is through arm 49, thence by a wire 101 to insulated post 84, thence by wire 91 to the binding-post 77, and thence by wire 92 to the binding-post 80 of 70 the lightning-arrester, and thence by wire 93 to the outgoing line 94.
- The circuit when the parts are in the active position, as indicated in Fig. 8, passes through the call-bell, the contact-arms 49 50, and the electromagnet 44, which are in series, and in consequence, while the contact-points of the arms 49 and 50 are joined, the magnet 44 will be energized and the magnet will be deenergized when the contact-points of these arms 80 49 and 50 are separated. The movement of the cam 36 causes the armature to be moved up mechanically to the magnet by contact of tooth 37 with pin 38 on dog 39, and the attraction of the magnet 44 holds the armature 85 43 against the poles of the magnet, and the armature will be retained in this position so long as the magnet is energized, and the rocking arm 45 being depressed while the armature is in contact with the magnet the winding-segment 25 is free to swing and will be moved in the direction shown by the arrow in Fig. 5 when the hook 10 is pulled downwardly, and will by this movement wind the spring 23. When the arm 16 has reached 90 the limit of its downward movement, a tooth 36' on a spring 37' on gear-wheel 27 will enter one of two holes 38' in cam 36 and cause the said wheel to turn with the cam as the latter is turned by the spring in reverse direction to 95 that in which the cam has been turned by the winding-segment when the arm 16 has been released from engagement with the dog 14 on the arm 9, as before described. The spring will set the train of gearing in motion, and the 100 disk 56, being turned in the direction of the arrow of Fig. 2, will cause the pins 55 to successively engage the tooth 54 on the arm 50 and will bring the contact-points 51 51 together, the contact of the points being maintained while each of the pins 55 is in engagement with the tooth 54 and the contact-points being separated by the disengagement of the tooth 54 and pin 55 as soon as the bottom of the tooth reaches the flat top surface 110 115 of the pin.
- The parts being constructed and arranged in the above-described manner and the box being in the passive condition, (shown in Fig. 7 of the drawings,) it will be observed that 120 the electric circuit through the various lines and contact-points is complete, the contact-points 51 51 of the arms 49 50 touching one another by reason of the fact that while the box is in its inactive position one of the pins 125 55 of the signal-wheel 56 being in this position of parts in contact with the tooth 54. There will therefore be a closed circuit through the arms 49 50; but this circuit will be short-circuited through the tongues 83 85. When 130

the outer door 2 has been opened, the pin 5, receding from the pin 6, permits the arm 66 to move, and this causes the contact-plate 67 to bridge the contact-points 61 62 and the contact-plate 68 to bridge the contact-points 63 64. The parts will thus by the opening of the door 2 be placed in condition for the sending of the proper signal, and this is accomplished in the following manner: The hook 10 being pulled downwardly, the arm 9 is moved, and the dog 14, contacting with the winding-arm 16, the latter will be depressed and will turn the shaft 22 and the cam 36 be revolved thereby, the tooth 37 will contact with pin 38 and depress the dog 39, thereby turning the shaft 40, throwing the armature 43 into contact with the cores of the magnet and at the same time drawing the arm 45 downwardly, so as to move the tooth 47 out of the path of the lug 25' on the winding-segment and allowing the latter to turn the pinion 21, and thereby winding the spring 22. The movement of the winding-segment is limited by the contact of the hook 25 on the end thereof with the post 26, and when the winding-segment has reached the extremity of its movement the tooth 36' on spring 37' enters one of the holes 38' in cam 36, and the cam and the gear-wheel 27 being now engaged the pinion 21, gear-wheel 29, and pinion 30 will be set in motion and will impart movement to the signal-wheel 56 and the escape-wheel 31, the rate of movement of the signal-wheel and the ratchet-wheel being governed by the pawl 32. The movement of the signal-wheel will cause that one of the pins 55 which has been in contact with the tooth 54 to pass the tooth, whereupon the contact-points 51 51 will be separated and the circuit broken until it is restored by the contact of the next-following pin 55, the contact being thus successively broken a number of times dependent on the number of pins on the signal-wheel. The particular alarm which will be sent from the signal-wheel shown is "17," and the amount of movement of the winding-segment is such that the signal-wheel will make four complete revolutions, thus repeating this particular alarm four times; but the number of pins on the signal-wheel and the number of revolutions which the same will make being of course variable at will. The movement of the winding-segment is limited by the contact of the first tooth of its toothed portion with the post 26, and the parts are so arranged that when the winding-segment stops the first pin 55 on the signal-wheel will rest, as before stated, in contact with the tooth 54.

From the foregoing description it will be observed that the winding-segment can only be turned to such point that the gearing will be in operative engagement with the volute spring 23 when the armature is in contact with the cores of the magnet. In the box 65 which is pulled first the armature will be drawn up against the cores of the electromagnet by the contact of the tooth 37 with the pin 38 on dog 39, and the arm 45 will be simultaneously depressed, so as to draw the tooth 47 out of the path of the lug 25' on the winding-segment, and the latter can thus be turned to the extremity of its movement. While the signal-wheel of the box that is in service is turning, the circuit through this box 75 will be broken during the greater part of the time, being only made during those brief intervals when the pins 55 are in contact with the tooth 54, and hence the armatures of all the other boxes on the line will be attracted 80 by their magnets if they are pulled while one box is in operation for such brief periods that there will not be sufficient time between the breaks of the line to pull any other box, and hence there can be no interference with the 85 operation of any box during the time an alarm is being sent therefrom.

Upon the back of the door 7 and below the arm 9 I arrange a small cylinder or dash-pot 9', within which is fitted a piston 10', that is 90 carried by a rod 11', that passes through the top of the cylinder or dash-pot and has a head 12', which sockets in a recess 13' in the edge of the arm 9. The purpose of this device is to prevent the box being wound by a 95 sudden jerk, the cylinder or dash-pot being filled with glycerin, so that if one attempted to jerk the arm 9 down suddenly the movement will be retarded by the resistance of the glycerin to the movement of the piston 10', the holes in the piston, however, allowing of the movement of the arm 9 at a reasonable rate of speed. Thus if it be attempted to pull one of the boxes with a sudden jerk while another of the boxes is in operation and during the time the line-circuit is closed the resistance which is offered to the movement of the arm 9 by the dash-pot will prevent the arm from moving through sufficient space to wind the box during the short period when 105 the line-circuit is closed.

Having fully described my invention, what I claim as new, and desire to secure by Letters Patent, is—

1. In a fire-alarm system, the combination with a main line, of a plurality of boxes arranged in series-circuit on said line, each box being provided with a pull-lever, a toothed segment movable thereby and a spring-motor adapted to be wound by the movement of 110 said segment for mechanically rotating a signal-wheel, and each box being provided with electrically-operable means so constructed and arranged that while one of said boxes is in operation, the electrically-operable means 115 of the other boxes will lock the said segment.
2. In a fire-alarm box, the combination of a normally unwound spring-motor for me-

chanically rotating a signal-wheel, means for winding said motor, means for locking said motor-winding means, an electromagnet and an armature, said armature being arranged 5 and adapted to operate said locking means at such time as the signal-wheel-rotating means is inactive, and electrical circuits and contacts operable by the signal-wheel-rotating mechanism to close the circuit through 10 said electromagnet.

3. In a device of the character described, the combination of a signal-wheel, clockwork mechanism for rotating said wheel, a contact-arm movable by said signal-wheel, an electromagnet in circuit with said contact-arm, a 15 lever carrying an armature, a member carried by the clockwork mechanism and adapted to be engaged by the armature-carrying lever when the electromagnet is deenergized, 20 and means whereby said armature-carrying lever will be mechanically moved within the sphere of attraction of said electromagnet by the winding of said clockwork mechanism.

4. In a device of the character described, 25 the combination of a signal-wheel, clockwork mechanism operably connected to said signal-wheel, a winding-segment meshing with the winding-arbor of said clockwork mechanism, a lug carried by said winding-segment, 30 a contact-arm adapted to be engaged by said signal-wheel, an electromagnet in a circuit adapted to be closed by said contact-arm, an armature-lever adapted to engage and lock on the winding-segment when the said electromagnet is deenergized, and means carried by 35 the clockwork mechanism for mechanically moving said armature-lever within the sphere of attraction of the electromagnet when the said winding-segment is moved to 40 wind the clockwork mechanism.

5. In a device of the character described, 45 the combination of a signal-wheel, clockwork mechanism operably connected to said signal-wheel, a winding-segment meshing with the winding-arbor of said clockwork mechanism, a lug carried by said winding-segment, a contact-arm adapted to be engaged by said signal-wheel, an electromagnet in a circuit which is closed by said contact-arm when the same is moved by the rotation 50 of the signal-wheel, a cam-disk carried on the winding-arbor of said clockwork mechanism, a contact carried by said armature-lever adapted to be engaged by said cam so as to 55 move the armature-lever within the sphere of magnetic attraction of said electromagnet

when the said cam is turned by the movement of the winding-arbor.

6. In a device of the character described, the combination of a clockwork mechanism, 60 means for winding the same, a signal-wheel mounted on one of the shafts of said clockwork mechanism, spring-actuated contact-arms, one of which is adapted to be engaged by the signal-wheel to close the contact 65 therebetween, an electromagnet in circuit with said contact-arms, contact-tongues arranged to shunt the circuit through said contact-arms, and an arm carried by one of the shafts of said clockwork mechanism and 70 adapted to maintain the shunt-circuit closed through said contact-tongues while the operating mechanism of the device is in passive condition.

7. In a device of the character set forth, 75 the combination with a signal-wheel, clockwork mechanism for imparting motion to said signal-wheel, a winding-segment mounted on the shaft and meshing with the clockwork mechanism, an arm carried on said 80 shaft, a pivoted lever, and a dog carried by said lever and adapted to engage with the arm of said shaft, of means for retarding the movement of said arm when the said arm is pulled to wind the clockwork mechanism. 85

8. In a device of the character set forth, 90 the combination of a signal-wheel, clockwork mechanism for rotating said wheel, contact-arms movable by said signal-wheels, an electromagnet in circuit with said contact-arms, an armature-lever pivotally mounted adjacent to said electromagnet, means carried by said armature for locking the winding-arbor of said clockwork mechanism, contact-posts arranged in series on the incoming 95 and outgoing circuit of said electromagnet, a spring-actuated switch-lever adapted to simultaneously establish contact between the contact-posts of the incoming and outgoing lines, a pin carried by said switch-lever, a box 100 inclosing said switch-lever, a hinged door carried by said box, and projections on the door to engage the pin on said switch-lever when the said door is closed so as to break the circuit through said contact-posts. 105

In testimony whereof I affix my signature in the presence of two witnesses.

STEPHEN J. HEINRICH.
